CLAIM

The ornamental design for a display screen with transitional graphical user interface for medical imaging equipment as shown and described.

DESCRIPTION

FIG. 1 is a first front view showing a display screen of a display screen with transitional graphical user interface for medical imaging equipment showing a first image in the sequence;

FIG. 2 is a second image thereof;

FIG. 3 is a third image thereof;

FIG. 4 is a fourth image thereof; and,

FIG. 5 is a fifth image thereof.

The outermost broken lines depict a display screen with transitional graphical user interface for medical imaging equipment in which the design is embodied that forms no part of the claimed design. The remaining broken lines illustrate portions of the graphical user interface that form no part of the claimed design.

The subject matter in this patent application includes a process or period in which an image changes into another image. This process or period forms no part of the claimed design.

1 Claim, 5 Drawing Sheets
